UNITED STATES PATENT OFFICE

EDWARD L. CULVER, OF LOS ANGELES, CALIFORNIA

BEAN CLEANING APPARATUS

Application filed November 27, 1928. Serial No. 322,122.

This invention relates to an apparatus for hereinafter, all of which contribute to produce an efficient bean cleaning apparatus. Heretofore it has been necessary to separate such dirt from the beans by hand. It has been attempted to accomplish this by screening, but some of the dirt clods are of sufficient size to prevent such an operation from being effective. The general object of this invention is to provide a special apparatus for effecting the separation of such dirt from beans. The invention is particularly adaptable for treating lima beans. Lima beans require very gentle rubbing because if the rubbing is not gentle enough the beans will become split. It is very important in treating them that such splitting should not occur because when in the form of whole beans, they will bring approximately ten cents per pound, whereas, the same beans after becoming split, cannot be sold for more than about one cent per pound. While, of course, these prices may vary, nevertheless the relative value of the split beans is greatly below the whole beans and for this reason the greatest care must be exercised in the construction and operation of an apparatus of this character to prevent splitting the beans.

One of the objects of the invention is to provide means for exerting a light rubbing action on the beans in such a way as to crush the small dirt clods, or nodules, without injuring the beans.

Apparatus embodying the invention is particularly useful in treating screened beans or screenings which have been separated from other beans by screening them, and these screenings contain a very large proportion of dirt. One of the objects of the invention is to provide apparatus particularly adapted for removing a relatively large quantity of dirt from beans by a single passage through the apparatus.

A further object of the invention is to improve the general construction of apparatus for this purpose.

Further objects of the invention will appear hereinafter.

The invention consists in the novel parts and combinations of parts to be described

A preferred embodiment of the invention is described in the following specification, while the broad scope of the invention is pointed out in the appended claims. 55

In the drawings:
Fig. 1 is a plan of apparatus embodying my invention.

Fig. 2 is a side elevation of the apparatus shown in Fig. 1 certain parts being broken away and shown in process. 60

Fig. 3 is a vertical section taken about in the plane of the line 3—3 of Fig. 1 upon an enlarged scale and particularly illustrating details of apparatus where the beans are fed into it. 65

Fig. 4 is a section taken about on the line 4—4 af Fig. 1 upon an enlarged scale and further illustrating details of the apparatus. In this view the upper end of the apparatus is broken away. 70

Fig. 5 is a cross section about on the line 5—5 of Fig. 4 taken at one edge of the screen and particularly illustrating details of the construction. 75

Before proceeding to a more detailed description of the present embodiment of the invention, it should be understood that according to my invention I employ two members between which the beans and dirt, or adobe clods, pass. These members are operated in such a way that the adobe clods will be crushed without injury to the beans. One of the members is preferably in the form of a screen and the other member has a soft construction which will enable it to present a yielding surface to the beans which can press the beans against the screen without injuring them, but which will exert sufficient force upon the clods to break the same on the screen to force them through the screen. This invention may be embodied in apparatus of various types. As there is a considerable variation in the size of the clods of adobe, or dirt, that is harvested with the beans, I prefer to give the beans a preliminary treatment in a feeder which operates to separate, or crush out the larger clods and I provide apparatus of a different type to 100

operate upon the beans and the clods of dirt remaining after preliminary treatment. However, it should be understood that this feeding apparatus performs more or less crudely the functions of the separator embodying my invention.

Referring to the drawings illustrating this embodiment of the invention, 1 indicates the frame of the apparatus which has an elongated, substantially horizontal portion 2, and a substantially vertical feeder frame 3.

The beans with the dirt, or adobe clods, are fed into a hopper 4 from which they are carried up by endless conveyor 5 and delivered into a feed hopper 6. Between this feed hopper and the lower portion of the apparatus I provide means which effects a separation of the beans from the larger clods of adobe. This portion of the apparatus includes an upper right screen which is preferably located in a vertical plane and cooperating with this screen I provide either a clothed roller or an endless belt, arranged so that the beans and dirt pass between the roller and the screen.

I prefer to employ two such upright screens, indicated at 7 in Figures 2 and 3. These screens are set up with their upper ends disposed adjacent to oppositely disposed openings 8 in the bottom of the hopper 6, and at these openings rollers 9 are located which carry the upper ends of two belts 10. These rollers rotate inwardly so that the inner runs 11 of the belt move downwardly along the faces of the corresponding screens. The runs 11 of the endless belts are backed up by backing boards 12 in the form of cross bars supported on yielding Z plates or backs 13, said backs being attached at their outer ends to an adjusting bar 14 supported on adjusting screws 15. These adjusting screws enable the position of the belts 11 to be adjusted toward the screens.

In the operation of the machine the beans and dirt pass down with the runs 11 of the belts and these belts operate to roll the adobe clods on the screen, and in this way tend to break them up and reduce the size sufficiently to enable them to pass through the screen 7.

All of the product of this feeding apparatus is dumped onto the upper end of a second screen 16, which is supported in the lower frame section 2. This screen is preferably supported in a fixed inclined position and is preferably subjected to rapid vibrations, that is to say, it is continuously shaken. Any suitable means may be employed for this purpose. In the present instance I provide an eccentric agitating device including a cross shaft 17 (see Fig. 4), carrying eccentrics 18 mounted in straps that are in the form of brackets 19, attached to bars 20 forming the under structure of a frame 21 that carries the screen 16. This frame 21 includes cross slats 22 on the upper edges of which the screen 16

lies. This screen, like the screens 7, is formed of wire mesh of sufficient gauge to prevent the beans from passing through it. The frame 21 also includes side boards 23 disposed at the side edges of the screen 16. Between these side boards 23 I provide a rubbing member 24 which is in the form of a wide "board". When the machine is in operation this board is moved so as to exert a rubbing action on the beans and adobe clods. Any suitable means may be employed for this purpose. It should operate to raise the rubbing board bodily out of contact with the beans on the upstroke and permit it to engage the beans on the downstroke. In the present instance I actuate this board by means of two pitman rods 25, the upper ends of which are attached to crank pins 26 on the side of two crank disks 27, the said disks being in the form of gear wheels 28 carried on a common shaft 29 and actuated by pinions 29 carried on a counter shaft 30. This counter shaft 30 is continuously driven by an endless belt 31 by a motor 32. The same motor drives a belt 33 that actuates the vibrating shaft 17 through the medium of a belt pulley 34.

The lower ends of the pitmans 25 are attached by pivot pins 35 to the upper side of the board 24. As the wheels 27 rotate it will be evident that the rubbing board 24 will move up and down on the inclined screen 16. I prefer to provide means so that on the upward movement of the rubbing board 24 it will be held away from the screen but permitted to contact with the screen on the downward movement. For this purpose I provide a frame 36 in the form of a yoke connected to the board 24. The sides of this frame are provided with a plurality of perforations 37, any one of which may receive a removable pin 38. This pin projects into the path of its corresponding pitman 25. As the pitman moves upwardly, as indicated by the arrow in Figure 4, it will engage this pin 38 and in this way raise the upper end of the rubbing board away from the screen.

In order to lift the lower end of the rubbing board away from the screen I provide a cam track in the form of an inclined bar 39 over each side board 23 and I provide the foot 40 of the rubbing board with a cross bar 41 having a tongue 42 at each side that projects out over the cam track. As the rubbing board moves toward the left, as viewed in Figure 4, this tongue 42 will ride up on the cam track 39 to about the point 43 where the tongue will pass out of the cam track at which point the lower end of the board will be permitted to fall onto the screen.

In order to increase the vibrating effect of the vibrating shaft 17 the screen frame 21 is supported on flexible slats 44, the upper ends

of which are supported on stanchions 45 running up from the side boards 23.

The under side of the rubbing board 24 is provided with clothing which preferably consists of an inner layer of relatively soft material, such as soft rubber, and an outer layer, or facing sheet, of fabric which comes in contact with the face of the screen and the beans. In order to increase the rubbing effect of the beans and clods together to reduce the clods and also to clean the surface of the beans, I prefer to provide the under side of the board with a plurality of pockets 46. These pockets may be simply small pockets formed on the under side and dispersed over the entire area of the board, but I prefer to have these pockets elongated and extending continuously across the board. Between the pockets the effective under surface of the board runs in the form of a plurality of rubbing faces 47. Each of these faces 47 is covered by an inner clothing 48 of soft rubber and the entire under face of the board is covered by a facing 49 of fabric which extends up and lines the pockets 46 and covers the under surface of the soft clothing 48.

The action of the pockets 46 is very important as regards the prevention of splitting the beans. In the operation of the apparatus the beans collect in these pockets and become gently rubbed on each other as the rubbing board moves to and fro. At the same time the beans collected in the pockets operate as a cushioning support for the rubbing board and keep it from approaching very closely to the face of the lower screen. By reason of the presence of these pockets it is therefore impossible for the rubbing board to rest on the upper sides of beans that have their under sides against the screen and the general effect is to produce a gentle rubbing of the beans between the rubbing board and the screen and at the same time rubbing them gently against each other to clean them.

At the lower end of the screen 16 the beans and any unseparated dirt passes on to a riddle 50 consisting of a plate 51 with perforations 52 in it. Below the riddle 50 a wire screen 53 is provided which may catch very small beans passing through the riddle.

When the apparatus is being used for cleaning screenings, that is to say, beans containing a very large percentage of dirt, which may be approximately 50%, the upright portion of the apparatus including the belts 10 and the screen 7 is particularly useful. In passing down from the hopper, the beans which are substantially flat do not turn over to any great extent as they pass along down the screen 7, but lie in a substantially flat position between the belts and the screen 7. The yielding pressure of the backing boards 12 against the beans and the dirt operates to break up the dirt particles or clods either adhering to the beans or associating with

them, and in this operation the surface of the screen 7 assists by attrition on the inner faces of the clods as they are advanced downwardly by the belts. The action of this part of the apparatus is quite different from that of the inclined screen illustrated in detail in Figure 4, in which the beans are rolled over and over on the inclined screen and accumulate in the pockets 46 where they rub the dirt between them and break up the clods.

After the screenings have passed through the upright portion of the apparatus and delivered to the inclined screen, they will have remaining only about 15% dirt. This 15% of dirt can be readily removed by the inclined screen and the rubbing board 24.

The inclined portion of the apparatus is not sufficiently efficient when used on beans carrying a large percentage of dirt and if used alone would necessitate a second passage, and possibly a third passage, of the beans over the inclined screen. The use of the upright portion of the apparatus enables bean screenings to be substantially clean in one passage through the machine.

From the lower end of the riddle the dirt passes over an inclined guide plate 54 onto a delivery spout 55 that delivers the beans into a receptacle.

The dirt passing from the screen 16 and 53 falls onto the upper run of an endless belt 56 that is continuously driven by the motor 32. This belt travels upwardly in an inclined direction on its upper side and passes over a roller 57 that delivers the dirt at the point 58 substantially under the point of the screen 16 on which the dirt and beans are dumped from the feeding apparatus on the feeder frame 3.

It is understood that the embodiment of the invention described herein is only one of the many embodiments this invention may take, and I do not wish to be limited in the practice of the invention, nor in the claims, to the particular embodiment set forth.

What I claim is:

1. In an apparatus for separating beans from small dirt clods gathered with the beans, the combination of an inclined screen, means for feeding the beans and clods down the screen, a rubbing member resting on the beans and clods, means for actuating the rubbing member to move downwardly on the screen while in engagement with the beans and clods and operating to reduce the clods and enable the same to pass through the screen, said rubbing member having flat rubbing faces with pockets between the same on its under side said pockets capable of containing quantities of the beans and clods and operating when the rubbing member moves to produce attrition of the beans and clods in the pockets to reduce the clods.

2. In an apparatus for separating beans from small clods of dirt gathered with the beans, the combination of an inclined screen,

means for feeding the beans and dirt onto the screen, a rubbing member resting on the beans and dirt on the screen, and means including a cam located near the lower end of the screen for periodically lifting the rubbing member bodily away from the screen at both ends on the upstroke and return the same to the screen with a movement along the screen on the downstroke to exert a rubbing action on the dirt and beans.

3. In an apparatus for separating beans from small clods of dirt gathered with the beans, the combination of a screen, means for feeding the dirt and beans onto the screen, a rubbing member resting on the dirt and beans on the screen, a pitman pivotally connected to the upper side of the rubbing member, a shaft and crank pin connected with the other end of the pitman for actuating the same to reciprocate the rubbing member on the screen, and means on the screen for engaging the side of the pitman and cooperating with the pitman and rubbing member to lift the rubbing member bodily off of the screen on one stroke and to permit the rubbing member to engage the screen on the other stroke.

4. In an apparatus for separating beans from small clods of dirt gathered with the beans, the combination of a screen, means for feeding the dirt and beans onto the screen, a rubbing member resting on the dirt and beans on the screen, a pitman pivotally connected to the upper side of the rubbing member, a shaft and crank pin connected with the other end of the pitman for actuating the same to reciprocate the rubbing member on the screen, a frame on the rubbing member having means for engaging the side of the pitman to lift one end of the rubbing member away from the screen on one stroke and a cam track with means on the rubbing member for engaging the same on the same stroke of the rubbing member to lift the other end of the rubbing member away from the screen, and cooperating to permit the rubbing member to descend onto the screen on the other stroke.

5. In an apparatus for separating beans from small clods of dirt gathered with the beans, the combination of a hopper with an opening in its bottom a pair of rollers in the said opening with upright screens, a pair of belts guided to move downwardly along the faces of said screens, means for feeding the beans with the dirt into the space between the belts and the screens.

6. In an apparatus for separating beans from small clods of dirt gathered with the beans, the combination of a hopper with a bottom opening, a pair of substantially vertical screens, a pair of rollers mounted in the bottom opening, an endless belt corresponding to each screen, means for guiding a run of each belt adjacent the face of its corre-

sponding screen and close to the same, and means for driving the belts so that the run of the belt adjacent the screen moves downwardly, and operating to drive the rollers to rotate inwardly on their upper sides, and means for feeding beans with the dirt into the space between the screens and the belts.

7. In an apparatus for separating beans from small dirt clods gathered with the beans, the combination of a relatively fixed inclined screen, means for feeding the beans with the dirt onto the upper portion of the screen, a rubbing member resting on the beans and dirt clods on the screen, means for moving the rubbing member along the screen to crush the clods and enable the same to pass through the screen, and an eccentric agitating device for imparting vibrations to the relatively fixed screen in a vertical and horizontal direction.

8. In an apparatus for separating beans from small dirt clods gathered with the beans, the combination of an inclined screen, means for feeding the beans and clods down the screen, a rubbing member resting on the beans and clods and means for actuating the rubbing member to move upwardly including cam means at the lower end of the rubbing member, for raising the same bodily at both ends out of contact with the beans, and on the downstroke permitting the rubbing member to rest on the beans and clods, and operating to reduce the clods and enable the same to pass through the screen.

9. In an apparatus for separating beans from small dirt clods gathered with the beans, the combination of an inclined screen, means for feeding the beans and clods down the screen, a rubbing member resting on the beans and clods, means for actuating the rubbing member to move downwardly on the screen while in engagement with the beans and clods and operating to reduce the clods and enable the same to pass through the screen, said rubbing member having flat rubbing faces with pockets between the same on its under side, said pockets capable of containing quantities of the beans and clods, operating when the rubbing member moves to produce attrition of the beans and clods in the pockets to reduce the clods, and means for agitating the screen in a vertical and horizontal direction.

Signed at Los Angeles, California this 9th day of November 1928.

EDWARD L. CULVER.
